Filed May 25, 1966, Ser. No. 2,429

Term of patent 14 years

U.S. Cl. D33—3
Int. Cl. D8—03

FIG. 1

FIG. 2

FIG. 3

FIG. 4

FIGURE 1 is a top plan view of a shelf support showing my design;

FIGURE 2 is a side elevational view;

FIGURE 3 is an end elevational view; and

FIGURE 4 is a perspective view thereof.

The opposite side of the shelf support is similar in appearance to the side shown in FIG. 2.

The design is characterized by an elongated sloped shelf support member in combination with a cup member seating the end of said support member, substantially as shown.

I claim:

The ornamental design for a shelf support, substantially as shown and described.
